UNITED STATES PATENT OFFICE.

GEORGE F. SPEER, OF FORT WORTH, TEXAS, ASSIGNOR TO THE INTERNATIONAL TUNNEL MACHINE COMPANY, A CORPORATION OF COLORADO.

TUNNEL-DRIVING MACHINE.

1,072,050.

Specification of Letters Patent.

Patented Sept. 2, 1913.

Application filed December 24, 1910. Serial No. 599,197.

To all whom it may concern:

Be it known that I, GEORGE F. SPEER, a citizen of the United States, residing at Fort Worth, county of Tarrant, and State of Texas, have invented certain new and useful Improvements in Tunnel-Driving Machines, of which the following is a specification.

My invention relates to improvements in tunneling machines.

10 In the United States patent to George A. Fowler, No. 891,473, entitled tunnel driving machine, an apparatus is described which comprises in general a main frame with supporting and driving wheels, a bank of 15 pneumatic drills presented forwardly from the main frame, an oscillating drill block with mechanism for automatically swinging the drills above a vertical axis from one side to the other, and a pulsator for supplying 20 the operating fluid to the drill actuating means.

The machine forming the subject matter of the present application is of the general type set forth in said prior United States 25 patent and embodies the same general principles in simplified form. The invention resides not only in specific details of novelty but at the same time in the bringing together into coöperative relation certain elements of construction which when so combined constitute a machine of extreme simplicity and effectiveness.

30 The apparatus forming the subject matter of the present application comprises a drill head for use in machines of the general type set forth in said prior United States patent. I have shown the same herewith as embodied in a complete machine, the latter having certain novel features which will be set forth 35 and claimed in a divisional application.

An embodiment of the invention is illustrated by way of example in the accompanying drawing, in which—

Figure 1 is a side elevation of the tunneling machine. Fig. 2 is a plan view of the same with parts removed. Fig. 3 is a vertical section through a coupling in a conduit from the pulsator to the manifold to be hereinafter described, showing the means 45 for tightening the packing. Fig. 4 is an elevation showing a portion of one of the manifolds with the coupling in section to illustrate the securing ring by which the coupling is held together. Fig. 5 is a detail 50 plan view of a portion of the gland. Fig. 6

is a plan view of the automatic feed and reverse mechanism by which the system of drills is oscillated upon its vertical axis. Fig. 7 is an elevation of the same. Fig. 8 is a side elevation of the oscillating drill support, and Fig. 9 is a front elevation of the same.

Referring especially to Figs. 1 and 2, 10 indicates the main frame of the machine, 11 the forward supporting wheels and 12 the rear supporting and propelling wheels, the latter being journaled in bearing blocks 13 which are vertically adjustable in ways 14 under the control of shafts 15 threaded into bearing 16 of the main frame, 10 so that upon rotation of the shaft 15 in one direction the bearing blocks 13 will be permitted to rise under the weight of the machine and rotation in the other direction will lower the bearing blocks in the machine. 15 From Fig. 2 it will be noted that two bearing blocks are provided for each wheel and their respective controlling shafts have secured to them the gear wheels 17 in mesh with each other, whereby they are caused 20 to move in unison. The shafts 15 must, therefore, be oppositely threaded in their bearings 16 so that they will be raised or lowered in unison. Any suitable means 25 may be employed to effect the operation of this adjusting mechanism, as for example, the provision of a squared end 18 on one of the shafts 15, as illustrated in Fig. 1, thus adapting it to manual actuation by means 30 of a wrench or the like. It will be understood that a precisely similar adjustment mechanism is provided for each of the rear 35 wheels 12 and that the two wheels may be adjusted in unison or independently of each 40 other.

Wheels 12 are suitably fixed to the driving axle 19 which has fixed thereon a worm wheel 20 engaging a vertically disposed worm 21 driven by worm wheel 22, which in turn is driven from worm shaft 23 by 45 means of sprocket wheel 24, chain 25 and sprocket wheel 26 from suitable power 27, as for example, pneumatic or electric motor. It will be apparent that the operation 50 of the motor 27 thus operates through the connecting means described, the worm wheel 20 which being fixed on shaft 19 causes the rotation of the shaft and its 55 wheels 12 to propel the machine forward or backward.

The main frame 10, as shown in Fig. 1, has projecting forwardly from it brackets 28 and 29 which are perforated at their ends to form vertical bearings for the axial pins about which the supports for the drill blocks oscillate as will appear. The oscillating drill support is illustrated in Figs. 8 and 9, and as shown therein is in the form of a U-shaped casting having arms 30 and 31 which rest upon the brackets 28 and 29 and have vertical perforations which are adapted to receive the axial pins by which the support is pivoted in the brackets 28 and 29. The vertical portion 32 of the drill support is provided with rectangular recesses at each side arranged in staggered relation for the reception of the drill boxes 33, which are shaped to conform with the recesses and held in place by the retaining plates 34 bolted against the side of the support. The drill boxes have piston chambers provided with pistons 35 which actuate the drills 36 in well known manner. Referring to Figs. 1 and 8 it will be observed that the drills are arranged on the arc of a circle or in some other form, which will provide sufficient clearance for the machine. In Fig. 2 it will be seen that they are also arranged in two vertical groups which, as will be shown, are actuated alternately by the pulsator.

Referring to Figs. 1 and 2, 37 indicates an electric or other suitable form of motor, the shaft of which is provided with pinion 38 meshing with the gear wheels 39 and 40 of the pulsator cylinders 41 and 42. The pistons of the cylinders 41 and 42 are driven alternately so that during one half of the cycle one cylinder is compressing above and exhausting below, while the other one is exhausting above and compressing below. The pulsator cylinders 41 and 42 are connected by jointed conduits with manifolds which distribute the alternate compression and exhaust to the piston chambers, as illustrated in Figs. 1 to 5 inclusive. Cylinder 41 has connected with it upper and lower conduit sections 43 and 44 while the cylinder 42 has similarly connected with it the conduit sections 45 and 46. These conduit sections terminate in line with the axis upon which the drill support oscillates, and at such point of termination they are connected by means of a pivotal union with conduit sections 47, 48, 49 and 50 which latter lead to the distributor manifolds 51, 52, 53 and 54. As shown in Figs. 3 and 4 each of the first mentioned group of conduit sections is provided at its ends with an interior annular rabbet and an exterior annular flange 55, while the adjacent end of the section to be joined to it is provided with an inner annular flange 56 which fits into the rabbet of the other section and an exterior annular flange 58 which incloses

the annular flange 55, and provides space for a body of packing 59 and gland 60. The gland and packing are held in place by a halved retaining ring or collar 61 which is secured by bolts 62 and studs 63 with nuts 64 to the annular flange 58, the bolts and studs passing through peripheral recesses 65 in the base of gland 60. For the purpose of tightening the packing the base of the gland 60 is further provided with threaded perforations 66 in which operate the threaded ends of screws 67 which have intermediate flanges 68 seated in countersinks in the retaining ring 61. By turning the screws 67 in their sockets the gland is thereby forced against the packing 59 and an air tight junction thus obtained. It will be observed that by the construction shown and described the gland 60 and retaining ring 61 are fixed to the movable section of the conduit and hence move with it about the axis of oscillation.

In order to actuate the two vertical groups of drills alternately, as hereinbefore referred to, it is obvious that compressed air should be introduced into the piston chambers behind the pistons in one group at the same time compressed air is introduced into the piston chambers in front of the pistons in the other group, and vice versa, when the space in front of the piston in one group is supplied with compressed air the space behind the other group must be supplied with compressed air. For this purpose the manifold 51 is connected by distributor pipes 69 with the rear end of all the piston chambers at the right hand side of the drill support, whereas manifold 54 is connected by distributor pipes 70 with the forward end of all the piston chambers at the left hand side. Assuming that at a given time the air in manifold 51 is under compression, the air in manifold 54 will also be under compression, whereas the air in manifolds 52 and 53 will be exhausted. Manifold 52 is accordingly connected by distributor pipes 71 with the rear end of all the piston chambers at the left of the drill support, whereas manifold 53 is connected by distributor pipes 72 with the forward end of all the piston chambers at the right. Consequently the drills at the right are advancing while those at the left are being retracted and vice versa.

Referring to Figs. 1, 6, 7 and 8 it will be seen that the arm 31 of the drill support has integral therewith or fixed thereto a worm wheel segment 73 which is operated by worm 74. Worm 74 is fixed to or integral with worm shaft 75 which is geared to electric or other motor 76. The operation of motor 76 is thus to rotate the worm wheel segment 73 which in turn swings the drill support from one side to the other. When the drill support completes its movement in one direction, the motor 76 is automatically reversed

as by reversing switch 77 operated by projecting fingers 78 of worm wheel segment 73.

For removing the chippings a scoop or pan 79 is mounted beneath the system of 5 drills, from which leads a suction pipe 80.

What I claim is:

1. The combination of a drill support having rectangular recesses for the reception of rectangular drill boxes, a plurality of 10 rectangular drill boxes with attached drills disposed in said recesses, and means for securing the drill boxes in said recesses.
2. The combination of a drill support having a plurality of vertical series of rectangular recesses, those of one series being in 15 staggered relation to those of another, a plurality of rectangular drill boxes with attached drills disposed in said recesses and means for securing the drill boxes in place.
- 20 3. The combination of a drill support having a vertical series of rectangular recesses

open at one side, a system of rectangular drill boxes with attached drills disposed in said recesses, and securing plates projecting over the edges of adjacent recesses bolted to 25 the drill support for securing the drill boxes in place.

4. The combination of a drill support having at each side a vertical series of rectangular recesses, those of one series being in staggered relation to those of the other, a vertical series of rectangular drill boxes with attached drills disposed in each of said series of recesses, and retaining plates projecting over the edges of adjacent recesses at each 30 side of the drill support, and bolted to the drill support for holding the drill boxes in place.

GEO. F. SPEER.
